John C. Denney.

UNITED STATES PATENT OFFICE.

JOHN T. FITZPATRICK, OF WORCESTER, MASSACHUSETTS.

ROOF CAST-IRON SOIL-PIPE CONNECTION.

SPECIFICATION forming part of Letters Patent No. 378,360, dated February 21, 1888.

Application filed October 28, 1887. Serial No. 253,588. (No model.)

To all whom it may concern:

Be it known that I, JOHN T. FITZPATRICK, a citizen of the United States, residing at Worcester, in the county of Worcester and State of Massachusetts, have invented certain new and useful Improvements in Roof Cast-Iron Soil-Pipe Connections; and I do hereby declare that the following is a full, clear, and exact description thereof, which, in connection with the drawing making a part of this specification, will enable others skilled in the art to which my invention belongs to make and use the same.

My invention relates to soil-pipe connections, and more particularly to the cast-iron soil-pipe connection which extends through the roof of a building for the purpose of ventilation and to carry off the impure gases from the traps or closets; and my invention consists in certain novel features of construction of that portion of the cast-iron soil-pipe connection which extends through the roof, as will be hereinafter fully described, and the nature thereof indicated by claims.

It will be understood by those skilled in the art that for the purpose of ventilation and to carry off the impure gases from traps and closets in a building cast-iron pipes are used, extending from said traps or closets up to and through the roof of the building. In order to prevent any leakage in the roof at the point where the pipe extends through, a sheet of lead or other similar material is placed upon the roof, through an opening in which the pipe extends, and said sheet of lead and the cast-iron pipe are united together in some manner, so as to form a tight joint and prevent any possible leakage at the point where the pipe extends through the roof.

In the use of cast-iron pipe in the manner above described considerable time and labor are required to make a tight joint at the point where the pipe extends through the sheet of lead or equivalent material on the roof, by reason of the great difficulty of uniting the cast-iron pipe with the sheet-lead through which the pipe extends, so as to form a perfectly water-tight joint.

The object of my invention is to construct the section of the cast-iron pipe which extends through the roof in such a manner that the same may be quickly and readily connected

with or united to the sheet of lead through which the pipe extends, and a perfectly watertight joint be made by the simple application 55 of a little solder and a solder-iron. I accomplish this result by combining with and making a part of the cast-iron pipe, at the point where it extends through the roof, a wrapping or coating of lead or analogous metal, encircling 60 said pipe in the manner to be hereinafter described.

The drawing represents an elevation, partly in section, of my improved cast-iron soil-pipe connection extending through a sheet of lead. 65

In the drawing, 1 is a section of a cast-iron-pipe connection of my improved construction. 2 is the cast-iron pipe proper, provided with a collar or flange, 3, upon its upper part, in this instance cast thereon and made a part 70 thereof, and a collar, 3', upon its lower part, in this instance made adjustable thereon and secured in place by means of a set-screw, 4.

Between the collar 3 and the collar 3' at the point where the pipe extends through the sheet 75 of lead 6, designed to be secured upon the roof of a building at the point where the soil-pipe 1 extends through the roof, a sheet of lead, 5, or analogous metal is wrapped around the pipe 2 and firmly secured thereon. Said 80 lead 5 encircles the pipe 2 and extends between the collars 3 and 3', and its exterior diameter as it encircles the pipe corresponds with the exterior diameter of the collars 3 and 3'.

I prefer to have the lower edge of the upper 85 collar, 3, grooved out, as shown, so that the upper edge of the lead 5 may extend up within the same, for the purpose of preventing any water getting in between said collar and the upper edge of the lead coating 5, to run down 90 between said coating and the pipe 2 and escape at the lower end thereof; but I do not limit myself to this construction. Neither do I limit myself to the employment of two collars, 3 and 3', for only one—the upper one, 95 3', which is upon the outside of the roof—may be used, and with very good results. Either one or both of the collars 3 and 3' may be cast upon and made a part of the pipe 2, or be made separate therefrom and secured thereto 100 in any well-known manner, and may be adjustable thereon. The coating 5, of lead or analogous metal, which surrounds the cast-iron pipe 2 at the point where it passes through

the sheet of lead 6 may be cast thereon or secured thereto in any ordinary and well-known manner.

The advantages of my improved construction of the cast-iron soil-pipe connection which extends through the roof of a building will be apparent to those skilled in the art. By combining with and making a part of the cast-iron pipe a coating of lead or analogous metal at the point where the pipe extends through the sheet of lead or analogous metal secured upon the roof of the building I am enabled to form a perfectly water-tight joint very quickly and cheaply around the pipe by simply uniting the two lead surfaces together by the application of a little solder and a solder-iron.

Having thus described my invention, what I claim as new, and desire to secure by Letters Patent, is—

- 20 1. As an improved article of manufacture, a cast-iron-pipe connection consisting of a cast-iron pipe, 2, provided with a collar, 3, thereon, and a wrapping of lead or analogous material, 5, encircling said pipe 2 and fitting 25 at one edge against said collar, so as to form a tight joint, for the purpose stated, substantially as shown and described.

2. As an improved article of manufacture, a cast-iron-pipe connection provided with two collars or flanges thereon, and a wrapping or 30 coating of lead or analogous metal encircling said pipe and extending between the two collars, for the purpose stated, substantially as shown and described.

3. The combination, with a pipe of cast-iron provided with two collars or flanges thereon, of a wrapping or coating of lead or analogous metal encircling said pipe and extending between said collars, for the purpose stated, substantially as shown and described. 40

4. The combination, with a sheet of lead or analogous metal having an opening therein, of a cast-iron pipe extending through said opening and provided with a wrapping or coating of lead or analogous metal encircling and 45 forming a part of said pipe at the point where it extends through said sheet of lead, for the purpose stated, substantially as shown and described.

JOHN T. FITZPATRICK.
